UNITED STATES PATENT OFFICE.

GASTON A. BRONDER, OF BROOKLYN, NEW YORK.

ELECTRICALLY-DRIVEN FLUID-MOTOR.

No. 832,653.

Specification of Letters Patent.

Patented Oct 9, 1906.

Application filed February 12, 1903. Serial No. 143,134.

To all whom it may concern:

Be it known that I, GASTON A. BRONDER, a citizen of the United States of America, and a resident of the borough of Brooklyn, county 5 of Kings, State of New York, have invented certain new and useful Improvements in Electrically-Driven Fluid-Motors, of which the following is a specification.

This invention relates to means with which 10 fluid-driven motors, working in closed cycles, are operated and controlled by means of electric currents. Its organization comprises the combination of a compressor, a fluid-driven motor working in a closed cycle, and 15 an electric motor by virtue of which the fluid-driven motor can be automatically supplied with the fluid for its propulsion.

Referring to the drawings, Figure 1 shows an elevation of the invention, partly in 20 section; and Fig. 2 represents a plan view of Fig. 1.

A tank is shown at 1, comprising a high-pressure compartment 2 and a low-pressure compartment 3. An air-compressor 4 has 25 its inlet-piping 5 leading from said compartment 3 and its discharge-piping 6 leading to the compartment 2. The compressor is shown to comprise two cylinders 25, from each of which extends a frame 26, supporting 30 a cross-head 27, secured to the end of the piston-rod 28. A connecting-rod 29 is journaled from the cross-head and connects with the crank 30 of the shaft 31 of the compressors.

35 A priming-pump 21 is attached to the air-compressor to supply air that is lost through leakage. The said priming-pump extends from the cylinder-head 32, and its piston-rod 33 is secured to the cross-head 34, from which 40 latter is journaled the eccentric-rod 35, having the eccentric 36, driven by the shaft 31. An inlet-opening is shown at 60, and the discharge-piping 61 connects with the piping 5.

An air-engine 7 is connected by piping 9 to 45 the high-pressure compartment 2, and its exhaust-opening is connected by piping 10 with the low-pressure compartment 3. The compartments 2 and 3 of the tank are connected by piping 22, and to the latter is fitted a reducing pressure-valve 23. A safety-valve 24 is attached to the compartment 2.

An electric motor 14 is geared with the 50 compressor 4 by means of the spur-gear 37 on the shaft 31, meshing with the pinion 38, mounted on the armature-shaft 39 of the said motor. Two feed-wires 15, with suitable wir-

ing and appurtenances to be described, furnish current to the electric motor.

Connected with the compartment 2 of the tank there is provided an electric pressure 60 gage 17, mounted on a base-plate 41. It comprises a curved hollow tube 18, that communicates with the pressure on the inside of the compartment by means of the piping 42. The said tube will elongate or contract with 65 variations of pressure in said compartment, and will thereby break an electric circuit when the pressure in the compartment reaches a predetermined point and in like manner will close the circuit when the pressure falls too low by virtue of the needle 43 70 making contact with the contact-point 44. The opening and closing of the circuit is communicated to a pilot - switch 19 and from thence to a circuit-breaker 20, although the 75 latter may be omitted.

The pilot-switch 19 is normally maintained in the position shown in Fig. 1, a solenoid 45 being mounted just above the same, the plunger 46 of which bears on the arms 47 80 of the said pilot-switch when the current is broken, thereby breaking the circuit at the contact-points 48 and stopping the supply of current to the motor 14.

One of the feed-wires 15 enters the hand-switch 50, and from the latter extends the wire 51, that connects with one of the arms of the pilot-switch 19. From the switch 50 also runs the wire 52 to the circuit-breaker 20, and the wire 53 extends from the circuit-breaker to one of the feeders 15. The solenoid 45 is connected by the wire 54 to the switch 50, and the wire 59 connects the contact-point 44 of the electric-pressure gage 17 with the solenoid. The needle 43 is connected 95 to the wire 51 by the wire 58. From the contact-points 48 there extend the wires 55 and 56, that lead to the electric motor 14.

To operate the invention, an electric current is taken from any suitable source and led 100 to the electric appurtenances that control the motor, which latter drives the compressor 4, that feeds the high-pressure compartment 2 of the pressure-tank 1, and the motor continues to run until the air-pressure in compartment 2 reaches a predetermined point, when the electric-pressure gage breaks the electric circuit and stops the motor. The pressure usually maintained in the said compartment 2 is about one hundred and fifty 105 pounds per square inch, and the air is expanded to about thirty pounds, at which pressure. 110

it exhausts from the engine 7 into the low-pressure compartment 3 of the tank. The air is thus operated in a closed cycle considerably above atmospheric pressure. Should the pressure in the compartment 2 rise above a certain point, it will be transferred to the compartment 3 by way of the piping 22 and reducing-valve 23, while at the same time the safety-valve 24 is fixed to the compartment 2 to prevent explosion should the other appurtenances controlling the pressures become inoperative.

Having described my invention, I claim—

1. The combination of an electric source of power, an electric motor, a compressor driven by the motor and operating in a closed cycle, a pressure-tank connected with the compressor, a high-pressure and a low-pressure compartment in the said tank, a pressure-reducing valve between the said compartments, an engine with its inlet connected with the high-pressure compartment, and its exhaust connected with the low-pressure compartment, connections between the inlet 15 of the compressor and the low-pressure compartment, connections between the discharge-outlet of the compressor and the

high-pressure compartment, an electric-pressure gage connected with the high-pressure compartment of the tank, and an electric switch controlled by the said gage to automatically close or break the electric circuit.

2. The combination of an electric source of power, an electric motor, a compressor driven by the motor, a pressure-tank, a high-pressure and a low-pressure compartment in said tank, connections between the inlet of the compressor and the low-pressure compartment, connections between the outlet of the compressor and the high-pressure compartment, an engine with its inlet connected with the high-pressure compartment and its exhaust connected with the low-pressure compartment, an electric-pressure gage connected with the high-pressure compartment, 35 a solenoid, a pilot-switch and electric connections between the motor, solenoid and pilot-switch.

Signed at New York, county and State of New York, this 6th day of February, 1903. 50

GASTON A. BRONDER.
